INVENTOR.

Lewis Pengilly
BY *George W. Webster*
ATTORNEY

UNITED STATES PATENT OFFICE.

LEWIS PENGILLY, OF STOCKTON, CALIFORNIA.

COMBINED CIGARETTE AND CIGAR LIGHTER.

Application filed January 12, 1924. Serial No. 685,882.

To all whom it may concern:

Be it known that I, LEWIS PENGILLY, a citizen of the United States, residing at Stockton, county of San Joaquin, State of California, have invented certain new and useful Improvements in Combined Cigarette and Cigar Lighters; and I do declare the following to be a full, clear, and exact description of the same, reference being had 10 to the accompanying drawings, and to the characters of reference marked thereon, which form a part of this application.

This invention relates to improvements in cigarette and cigar lighting devices especially designed to be installed on automobile dashboards, and particularly represents an improvement over that general type of device shown in my copending applications for patent on a cigarette lighter, filed February 5th, 1923, Serial No. 616,906, and on a cigar lighter, filed March 6th, 1923, Serial No. 623,212.

These devices are each provided with a fixed electric heating element, a suction cup aligned therewith, and means for supporting and moving a cigarette or cigar into engagement with the respective cup and element, thereby lighting the same.

The principal object of my present invention is to provide a single heating element for both a cigar and a cigarette lighting device of the above named character, and to mount and arrange said element in such a manner that while allowing it to be moved to have a definite and fixed position relative to either suction cup, it may be removed at will from either such position and drawn toward the operator without moving the device as a whole and without disconnecting the wiring to the element.

By means of this construction, not only may the element be used to light cigarettes or cigars supported to the respective devices, but it may be employed instead of a match 45 to light or relight a cigar or cigarette held in the mouth of the smoker at any reasonable distance from the device itself.

A further object of the invention is to produce a simple and inexpensive device and yet one which will be exceedingly effective for the purposes for which it is designed.

These objects I accomplish by means of such structure and relative arrangement of parts as will fully appear by a perusal of 55 the following specification and claims.

In the drawings similar characters of ref-

erence indicate corresponding parts in the several views:

Fig. 1 is a front view of the device.

Fig. 2 is an end view of the same.

Fig. 3 is a top plan view of the heating element unit or head, with the adjacent parts.

Referring now more particularly to the characters of reference on the drawings, the 65 numeral 1 denotes a plate having side ears 2 whereby it may be attached to a dashboard 3, and vertical end walls 4 projecting outwardly from the side edges of the plate.

Fixed on and projecting outwardly from 70 one wall 4 is a sleeve 5 having a longitudinally movable valve 6 therein, these members forming part of the suction unit especially featured in my copending application for patent filed January 12th, 1924, 75 Serial No. 685,883.

The other wall 4 is orificed as at 7 in alignment with the valve 5, the plate 1 having cigarette supporting members 8 between 80 said walls 4 and arranged to support a cigarette in alignment with the valve and orifice 7.

A cigarette container 9 and dispensing means operated by a knob or handle 10, are 85 mounted in connection with the plate 1 above the supports 8. These however form no part of the present invention, being particularly featured in my copending application for patent filed January 12th, 1924, 90 Serial No. 685,884, the device as a whole comprising a cigarette lighter of the general type shown in application, Serial No. 616,906.

Positioned behind the dashboard 3 is an 95 enclosed spring reel structure 11, any one of various designs to be found being suitable for my purpose.

The casing 11^a of this structure has a bracket 12, arranged to be secured to the dashboard in common with certain of the 100 ears 2 of the plate 1 by the screws or bolts 13 thereof, so as to hold said reel and plate in a definite relation to each other. The reel is positioned at the right hand side of the plate 1, or in a plane adjacent the orificed 105 wall 4.

Secured on the dashboard and projecting therethrough in the horizontal plane of the axis of the orifice 7 is a sleeve 14, communicating with the interior of the reel-casing 11^a, and rigidly secured thereto.

On the dashboard, alongside the orificed

wall 4, is a vertical plate 15, held in definite relation to the dashboard and end wall by the sleeve 14, which projects through the lower end of said vertical plate and has 5 a head or flange 16 on its outer end bearing thereagainst.

Additional or other means may however be employed to hold the plate 15 in place if desired.

10 At the upper end of the plate 15 is a downwardly facing suction cup 17, having members 18 guided in tubes 19 carried by the plate and enabling vertical movement of said cup being had, one of said members 15 being tubular and being connected to the same source of suction as is the valve 6.

The particular construction and adjustability of this suction cup however forms no part of the present invention.

20 Slidable in and removable from the sleeve 14 is a hollow stem 20 having at its outer end a head 21 and a handle member 22, the axial line of said head and handle being at right angles to that of the stem.

25 Mounted in the outer end of the head inwardly of the rim or edge thereof is an electric heating element 23, of suitable design, the lead wires for which are in the form of a cable 24, extending through the stem 20, and sleeve 14, and thence about the reel 30 11, the spring of the latter acting to keep the cable wound on said reel.

35 One outside wire 25 leads from a source of current to one of the cable wires through the reel structure in any suitable manner, while the other wire 26 similarly connected to the cable, leads to a contact strip 27 mounted on and insulated from the plate 1, said strip being arranged to be engaged by 40 the valve 6 when the latter is moved toward the orifice 7, and forming with said valve the switch whereby the circuit to the element 23 is opened or closed.

45 In operation, the stem 20 of the heater unit is normally seated in the sleeve 14, the element 23 then facing either the orifice 7 and cup or valve 6, or the cup 17. The sleeve 14 is so disposed relative to the adjacent plate-wall 4 that the outer rim of the head 50 16 will snugly engage said wall, so that the head can then have no movement which might cause annoying sounds with vibration, while the plate 15 is curved the same as the head, so that the latter can have a snug fit therewith when turned to face upwardly.

55 When the element is in either position, a cigarette or cigar may be placed between said element and the respective suction cup and lighted in the same manner as if said element were a permanently mounted fixture.

60 When it is desired to light or relight a cigarette or cigar held in the mouth, the smoker grasps the handle 22 and pulls the heating unit away from the fixtures and

up to the cigar, etc., the cable 24 unwinding from the reel. The same switch structure 6-27 is used to cause the element 23 to be heated as when said element is used in connection with the suction element, since 70 while said suction is not now being used, the unrestricted passage of air through the valves had when the latter is moved to close the switch, will do no harm. I have in mind, however, to provide a switch to be 75 mounted in the handle 22, should this be found desirable.

When the cigar, etc., is sufficiently ignited, the switch is thrown off, and the stem 20 of the heating unit returned to its normal seat 80 in the sleeve 14, facing either the suction member 6 or the cup 17, as may be desired.

From the foregoing description it will be readily seen that I have produced such a device as substantially fulfills the objects of 85 the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. In combination, a cigarette lighting device having a suction member, and a heating element adapted to be placed in opposed alinement with said member and to be removed from such position at will. 100

2. In combination, a cigarette lighting device having a suction member, a heating element adapted to be positioned in opposed alinement with said member and operable in such position, and means whereby said element may be withdrawn from such position without interfering with the operation thereof. 105

3. In combination, a cigarette lighting device having a suction member, an electric heating element arranged in a circuit and adapted to be positioned in opposed alinement with said member and to be removed from such position at will, and switch means for said circuit operable regardless of the 110 position of the element. 115

4. In combination, a cigarette lighting device having a suction member, a heating element, and means for enabling said element to be positioned in a positive relation to said member while allowing said element to be moved from such location at will. 120

5. In combination, a cigarette lighting device having a suction member, an electric heating element arranged in a circuit and adapted to be positioned in opposed alinement with said member, and to be removed from such position at will, and a reel structure on which the circuit wires for said element are wound. 125 130

6. In combination, a cigarette lighting device having a suction member, a sleeve mounted in fixed relation to said device at the side thereof opposite to said member, a heating element, and a stem arranged in connection therewith and removably seated in the sleeve.
7. In combination, a cigarette lighting device having a suction member, a sleeve mounted in fixed relation to said device at the side thereof opposite to said member, a heating element, a stem arranged in connection therewith and removably seated in the sleeve, and means whereby when the stem is seated the element will face the suction member.
8. In combination, a cigarette lighting device having a suction member, a sleeve mounted in fixed relation to said device at the side thereof opposite to said member, and in a plane at right angles to the axis thereof, a heating element, and a stem arranged in connection therewith and removably seated in the sleeve; the element being arranged relative to the stem to face said suction member when the stem is seated in the sleeve.
9. In combination, a cigarette lighting device having a suction member, an orificed wall provided with the device at the side thereof opposite to said suction member and facing the latter, a sleeve mounted in fixed relation to said wall and outwardly thereof, a heating element, a stem arranged in connection therewith and removably seated in the sleeve, and a head in which the element is mounted adapted to then abut against the outer face of the wall; the element facing the suction member through the wall-orifice.
10. In combination, a cigarette lighting device having a suction member, a heating element adapted to be positioned in opposed alinement with said member, and to be withdrawn from such position at will, and guide means for positively causing the element to assume said opposed position relative to the suction member.
11. In a cigarette and cigar lighting device, a stem, and a heating element mounted in connection with the stem and facing in a direction at an angle to the axis of the stem.
12. In a cigarette and cigar lighting device, a stem, a head thereon positioned in a plane at an angle to the axis of the stem, and a heating element mounted in the outer face of the stem.
13. In combination, a pair of suction cups disposed in spaced relation, and a heating element adapted to be seated in opposed alinement with either cup.
14. In combination, a pair of suction cups disposed in spaced relation, and a heating element adapted to be seated in opposed alinement with either cup, and to be withdrawn from said positions at will.
15. In combination, a pair of suction cups disposed in spaced relation, a heating element adapted to be moved to align with either cup at a time in opposed relation thereto, and a common means for seating and supporting the element in said positions.
16. In a cigarette lighting device, a body, an electric heating element arranged in a circuit and adapted to be placed in a predetermined position on the body and to be removed from such position at will.
17. In a cigarette lighting device, a body, an electric heating element arranged in a circuit and adapted to be placed in a predetermined position on the body and to be removed from such position at will, and switch means for the circuit operable regardless of the position of the element.

In testimony whereof I affix my signature.

LEWIS PENGILLY.
